CLAIM

The ornamental design for a headpone holder, as shown and described.

DESCRIPTION

FIG. 1 is a perspective view of a first embodiment of a headphone holder showing my new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof;

FIG. 8 is a perspective view of a second embodiment of a headphone holder showing my new design;

FIG. 9 is a front elevational view of the embodiment of FIG. 8;

FIG. 10 is a right side elevational view of the embodiment of FIG. 8;

FIG. 11 is a top plan view of the embodiment of FIG. 8;

FIG. 12 is a rear elevational view of the embodiment of FIG. 8;

FIG. 13 is a left side elevational view of the embodiment of FIG. 8;

FIG. 14 is a bottom plan view of the embodiment of FIG. 8; and,

FIG. 15 is a reference view of the embodiment of FIG. 8 wherein a headphone is held by the headphone holder. The headphone portion in broken lines on FIG. 15 is shown for an illustrative purpose only and is not a part of claimed design.
